UNITED STATES PATENT OFFICE.

ARCHIBALD G. SHAVER, OF CHICAGO, ILLINOIS, ASSIGNOR TO THE REGAN SAFETY DEVICES COMPANY, INC., OF NEW YORK, N. Y., A CORPORATION OF NEW YORK.

INDUCTION TRAIN-CONTROL SYSTEM WITH ROADSIDE APPARATUS.

Application filed October 10, 1921. Serial No. 506,598.

To all whom it may concern:

Be it known that I, ARCHIBALD G. SHAVER, a citizen of the United States, residing at Chicago, in the county of Cook and State of Illinois, have invented certain new and useful Improvements in Induction Train-Control Systems with Roadside Apparatus, of which the following is a specification.

This invention relates to induction train control systems, and more particularly to roadside mechanism employed in such systems for inductively transmitting energy to cooperative vehicle carried mechanism when the latter moves in proximity to the former in the movement of the vehicle or train on a roadway, and has special reference to the provision of roadside inductorium mechanism adapted for employment with train control systems of the type disclosed in my copending applications Serial No. 422,598 of Nov. 8, 1920 and Ser. No. 506,595 of Oct. 10, 1921.

Among the principal objects of the present invention are the provision of inductive roadside train control mechanism constructed for receiving energy from a vehicle energy source and for transmitting such energy back to the vehicle to influence and operate vehicle control means; the provision of such roadside mechanism operative for transmitting energy to the vehicle under "safety" track conditions and for inhibiting the transmission of such energy under "danger" track conditions; the further provision of such mechanism comprising an energy receiving inductorium and an energy transmitting inductorium so connected in circuit as to permit reversal of connections to change the phase relations in said circuit and to permit disconnection to inhibit the transmission of energy from one inductorium to the other; the still further provision of a roadside mechanism of this nature in which means are provided for correcting for phase displacement and power factor of the circuit so that a substantial amount of energy is transmitted to and re-induced in the train carried mechanism; and the provision of a roadside inductorium apparatus in which the induced impulses are of a character to effectively operate the train carried apparatus having especial utility with high speed trains.

To the accomplishment of the foregoing and such other objects as may hereinafter

appear, my invention consists in the elements and their relation one to the other, as hereinafter particularly described and sought to be defined in the claims, reference being had to the accompanying drawing which shows preferred embodiments of my invention, and in which:

Fig. 1 is a diagrammatic view of the roadside inductoriums showing part of the vehicle carried mechanism cooperating therewith,

Fig. 2 is a section on the line 2—2 of Fig. 1, and

Figs. 3 to 10 are views of modifications.

As disclosed in my copending applications above referred to, the roadside mechanism of my invention is constructed to be responsive to different track conditions such as "safe", "caution" and "danger" track conditions to cooperate with vehicle mechanism in the movement of the train for impressing different indications or effects on the train such as proceed, speed restrictive and "stop" effects in accordance with and in correspondence to the said track conditions. To accomplish these ends I provide for each section or block of the track a set of inductoriums such as the energy receiving inductorium 62^a and the energy transmitting inductorium 60^a, each of which may be about 50 feet in length and may comprise a coil wound upon linear cores as clearly shown in Fig. 1, the said inductoriums being connected in circuit and controlled by a signalling system so as to change circuit connections in response to varying track conditions, each set of roadside inductoriums being adapted for cooperation with companion vehicle carried inductoriums in the movement of the vehicle for receiving energy from a vehicle energy source and for transmitting such energy back to the vehicle for operating the train control means, the vehicle being provided to this end with the energy transmitting inductorium 62 adapted for inductive cooperation with the roadside receiving inductorium 62^a as shown in Figs. 1 and 2, and the vehicle energy receiving inductorium 60 adapted for inductive cooperation with the roadside transmitting inductorium 60^a. The construction of the vehicle system is such that if energy is transmitted to the energy receiving inductorium 60 in one direction or in a given phase, proceed effects are produced on the

train, and if such energy is transmitted in an opposite direction or in an opposite phase, speed restrictive effects are produced on the train; and if no energy is transmitted, 5 "stop" effects are produced for bringing the train to a halt. For transmitting energy from one roadside inductorium to the other in a given direction or phase, for modifying the direction or phase in which such 10 energy is transmitted, and for inhibiting the transmission of such energy, I provide circuit connections between the roadside inductoriums as heretofore referred to, with means for reversing said circuit connections 15 and for disconnecting the inductoriums responsive to roadside conditions, such means comprising a pole changer including the contacts 74 and 75 under the control of a distant relay D and a circuit make and break 20 device including the contacts 72 and 73 under the control of a home relay H.

Under "safety" track conditions with the relays D and H energized, the inductoriums 60^a and 62^a are connected by the circuit including the coil of the inductorium 62^a, conductor 35, contact 75 closed in attracted position, conductor 34, closed contact 73, conductor 33, the coil of inductorium 60^a, conductor 39, contact 72 closed, conductor 38, contact 74 closed in attracted position, and conductor 36 to the coil of inductorium 62^a, the closing of this circuit being effective 30 for transmitting energy from inductorium 62^a to inductorium 60^a in a given direction or phase.

Under "caution" track conditions the distant relay D is deenergized and the contacts 74 and 75 controlled thereby are actuated to released position, this being effective 40 for reversing the circuit connections between the inductoriums by the engagement of the contacts 74 and 75 with the conductors 35 and 40 respectively, this reversal of connections between the inductoriums resulting in 45 the transmission of energy from the receiving inductorium 62^a to the transmitting inductorium 60^a in an opposite direction or phase.

Under "danger" track conditions with the relay H deenergized, the contacts 72 and 73 are opened, disconnecting the inductoriums 62^a and 60^a and resulting in the inhibiting of transmission of energy from one to the other.

For the purpose of correcting for phase displacement and power factor in the inductorium circuit, I provide circuit modifying means such as shown in the alternative arrangements of Figs. 3 to 10 of the drawings. In Fig. 3 the receiving and transmitting inductoriums 62^a and 60^a respectively are provided with secondary circuits each of which may comprise a coil 100 wound about the core of the inductorium and a condenser 101 connected to said coil. With this con-

struction each inductorium is in effect a transformer, and the secondary circuit functions to correct the phase displacement and power factor.

In Fig. 4 I show a modification of Fig. 3 70 with the employment of a multiple inductorium system, both the transmitting and receiving inductoriums being divided into a plurality of sections or elements, the inductorium elements being arranged in 75 tandem as shown in the figure and connected in series with the pole changing and make and break switch means controlled by the distant and home relays D and H respectively. Each of the inductorium elements 80 may be also provided with phase displacement and power factor correcting means of the type shown in Fig. 3, the energy transmitting inductorium elements being to this end provided with the secondary coils 102 85 and the condensers 104 connected thereto, and the energy transmitting inductorium elements being each provided with a secondary coil 103 and a condenser 105 connected thereto. It has been found by experimentation that where an inductorium is 90 divided in this manner into a plurality of sections or elements, that under similar operating conditions, as for example with the same amount of energy used, the multiple inductorium system produces impulses 95 of greater amplitude, this being especially desirable for high speed trains. More specifically, where a single inductorium is used the impulse with a given amount of energy 100 employed may be represented by a long flat curve, and where such inductorium is divided into two sections or elements with the sum of the length of the sections being substantially equal to the length of the single section, the successive impulses 105 produced will each be of greater amplitude, this being a desirable characteristic in the operation of a train control element such as a relay, and at high speeds the succession of 110 waves will tend to merge together to produce an impulse having an effective greater length than the impulse produced with a single inductorium. The inductorium elements in tandem may be arranged in series as shown in Fig. 4, or may be differently arranged as indicated in the modifications to be described hereinafter.

In Fig. 5 of the drawings for the purpose 115 of correcting for phase displacement or power factor of the inductorium circuit a condenser 106 is arranged in parallel with one of the inductoriums, as for example, the energy receiving inductorium 62^a, said condenser being connected to the conductors 107 120 and 108 which lead to the energy transmitting inductorium 60^a.

In Fig. 6 the parallel arrangement of the condenser shown in Fig. 5 is combined with 125 the tandem arrangement of the inductorium 130

elements. In this arrangement the coil elements of the inductorium 62^t are provided with condensers 113 and 114, the coil elements of this inductorium being connected to the coil elements of the inductorium 60^t in independent circuits, one set of coil elements being controlled by the outer set of make and break contacts 109 and 110, and the outer set of pole changing contacts 111 and 112, and the other set of coils being independently controlled by the inner set of make and break contacts 109 and 110 and by the inner set of pole changing contacts 111 and 112, the construction in Fig. 6 being in effect Fig. 5 duplicated in tandem.

In the arrangement shown in Fig. 7 a condenser 115 is introduced in series with both inductoriums 60^t and 62^t to accomplish the same results. In the arrangement shown in Fig. 8 the inductoriums 62^t and 60^t are divided into a plurality of elements arranged in tandem, the elements of the inductoriums being connected in independent circuits through the relay controlled make and break and pole changing switches, Fig. 8 comprising a construction in which a plurality of circuits as shown in Fig. 7 are arranged in tandem.

In Fig. 9 one of the inductoriums 60^t or 62^t is provided with a shunt circuit 116 including a transformer 117, to the secondary of which is connected the condenser 118, this arrangement also providing for a correction of phase displacement and power factor of the inductorium circuit.

The arrangement shown in Fig. 10 is in effect Fig. 9 duplicated in tandem, the inductoriums 60^t and 62^t each comprising a plurality of elements, each of the elements of the inductorium 60^t being provided with a secondary or shunt circuit such as 116 embodying the transformer 117 to the secondary of which is connected the condenser 118.

While I have herein referred to coil 62^t as the energy receiving inductorium and the coil 60^t as the energy transmitting inductorium, it will be obvious that these coils so function for a given direction of movement of the train or vehicle. It will be further obvious that with the movement of a vehicle in the opposite direction, the coil 62^t is an energy transmitting inductorium and the coil 60^t is an energy receiving inductorium, the roadside inductoriums thus being constructed and adapted to be utilizable with trains moving in both directions; the roadside inductorium system herein described being furthermore equally applicable with movement of trains in either direction, irrespective of whether the locomotive is moving stock or tender first.

While I have shown my device in the preferred forms, it will be apparent that many changes and modifications may be made in the structure disclosed, without departing

from the spirit of the invention, defined in the following claims.

I claim:

1. In an inductive train control system, roadside mechanism comprising an energy receiving inductorium and an energy transmitting inductorium, roadside means operable in response to track conditions for connecting the inductoriums in circuit under a "safety" track condition and operative to disconnect the same under a "warning" track condition. 70

2. In an inductive train control system, roadside mechanism comprising a plurality of inductoriums, and means for connecting the same operative to reverse circuit connections therebetween. 80

3. In an inductive train control system, roadside mechanism comprising a plurality of inductoriums, and means for connecting the same operative to reverse circuit connections therebetween and for breaking circuit connections therebetween. 85

4. In an inductive train control system, roadside mechanism comprising a plurality of inductoriums, and means for connecting the same operative to reverse circuit connections therebetween and for breaking circuit connections therebetween, the said means comprising a pole changer and a make and break device. 90

5. In an inductive train control system, roadside mechanism comprising a plurality of inductoriums connected in circuit, one of said inductoriums being an energy transmitting and the other of said inductoriums being an energy receiving inductorium, roadside means operable in response to track conditions for connecting the inductoriums in circuit under a "safety" track condition and operative to disconnect the same under an "unsafe" track condition, and means for correcting for phase displacement or power factor of said circuit. 100

6. In an inductive train control system, roadside mechanism comprising an energy receiving inductorium, an energy transmitting inductorium connected in circuit thereto, and means for correcting for phase displacement or power factor of said circuit. 110

7. In an inductive train control system, roadside mechanism comprising an energy receiving inductorium, an energy transmitting inductorium connected in circuit thereto, means for changing circuit connections between said inductoriums, and means for correcting for phase displacement or power factor of said circuit. 120

8. In an inductive train control system, roadside mechanism comprising an energy receiving inductorium, an energy transmitting inductorium connected in circuit thereto, and means for correcting for phase displacement or power factor of said circuit, the said correcting means including a con- 125

- denser electrically connected to said circuit for compensating the lag therein.
9. In an inductive train control system, roadside mechanism comprising an energy receiving inductorium, an energy transmitting inductorium connected in circuit thereto, means for changing circuit connections between said inductoriums, and means for correcting for phase displacement or power factor of said circuit, the said correcting means including a condenser electrically connected to said circuit for compensating for the lag therein. 65
10. In an inductive train control system, roadside mechanism comprising a plurality of inductoriums connected in circuit, a plurality of magnet controlled switches operable in response to track conditions for changing circuit connections between said inductoriums, and means for correcting for phase displacement or power factor of said circuit. 70
11. In an inductive train control system, roadside mechanism comprising a plurality of inductoriums connected in circuit, means operable in response to track conditions for reversing circuit connections and for opening circuit connections between said inductoriums, and means for correcting for phase displacement or power factor of said circuit. 75
12. In an inductive train control system, roadside mechanism comprising a plurality of inductoriums connected in circuit, a pole changer and a make and break device operable in response to track conditions for reversing circuit connections and for opening circuit connections between said inductoriums, and means for correcting for phase displacement or power factor of said circuit. 80
13. In an inductive train control system, roadside mechanism comprising an energy receiving inductorium, an energy transmitting inductorium connected in circuit thereto, means for reversing circuit connections and for breaking circuit connections between the inductoriums, and means for correcting for phase displacement or power factor of said circuit. 85
14. In an inductive train control system, roadside mechanism comprising an energy receiving inductorium, an energy transmitting inductorium connected in circuit thereto, and means for correcting for phase displacement or power factor of said circuit, the said correcting means including a secondary circuit associated with an inductorium active for compensating for the current lag therein. 90
15. In an inductive train control system, roadside mechanism comprising an energy receiving inductorium, an energy transmitting inductorium connected in circuit thereto, and means for correcting for phase displacement or power factor of said circuit. 95
16. In combination, roadside apparatus for impressing roadside conditions on moving vehicles comprising a plurality of connected inductorium elements arranged in alinement longitudinally of the track and spaced closely adjacent each other for producing successive and cumulative impulses in a vehicle carried mechanism, and means for correcting for phase displacement or power factor of said elements. 100
17. In combination, roadside apparatus for impressing roadside conditions on moving vehicles comprising roadside energy transmitting inductorium means and roadside energy receiving inductorium means connected thereto, each of the said inductorium means comprising a plurality of inductorium elements arranged in tandem, and means for correcting for phase displacement or power factor of said inductorium means. 105
18. In combination, roadside apparatus for impressing roadside conditions on moving vehicles comprising a plurality of roadside energy receivers arranged in tandem, a plurality of roadside energy transmitters arranged in tandem, means for selectively connecting the said receivers in circuit with the said transmitters and means for correcting for phase displacement or power factor of said circuit. 110
19. In combination, roadside apparatus for impressing roadside conditions on moving vehicles comprising a plurality of roadside energy receivers arranged in tandem, a plurality of roadside energy transmitters arranged in tandem, means for selectively connecting the said receivers in circuit with the said transmitters, provisions for disconnecting the receivers from the transmitters, and means for correcting for phase displacement or power factor of said circuit. 115
20. In combination, roadside apparatus for impressing roadside conditions on moving vehicles comprising a plurality of inductorium elements connected in circuit and arranged in alinement longitudinally of the track and spaced closely adjacent each other for producing successive and cumulative impulses in a vehicle carried mechanism, and means for correcting for phase displacement or power factor of said circuit, the said means comprising a condenser connected to said circuit for compensating for the current lag therein. 120

In testimony whereof I affix my signature.

ARCHIBALD G. SHAVER.
